UNITED STATES PATENT OFFICE.

JOHN HEALY, OF NEW YORK, N. Y.

DESIGN FOR A BOX-COUCH FRAME.

SPECIFICATION forming part of Design No. 25,040, dated January 7, 1896.

Application filed December 2, 1895. Serial No. 570,861. Term of patent 14 years.

To all whom it may concern:

Be it known that I, JOHN HEALY, a citizen of the United States, residing at New York, in the county of New York and State of New York, have invented and produced a new and original Design for Frames for Box-Couches, of which the following is a specification.

This invention relates to a design for a frame for box-couches, and the design consists in the configuration as herein described, and shown in the accompanying illustration, in which the figure is a perspective view of a box-couch frame illustrating my design.

The leading feature of my design is an upwardly and outwardly flaring box-like closure having a projecting rim and with feet depending from the corners of said rim.

The frame which is here represented consists of an oblong rectangular rim A and

downwardly and inwardly projecting sides B and bottom portion C, the whole disclosing an upwardly and outwardly flaring closure having its rim projecting therefrom. At each corner of said rim are seen the legs D.

The top of the box consists of the oblong 25 and rectangular frame E of substantially the configuration of the rim A, all as shown in the accompanying illustration.

Having thus described my design, what I claim is—

The design for a box couch frame, substantially as shown and described.

In testimony whereof I affix my signature in the presence of two witnesses.

JOHN HEALY. [L. S.]
